PIANO BENCH

Virgil D. Belfield and Elsie Belfield, Elkhorn, Wis.

Application March 7, 1946, Serial No. 652,696

4 Claims. (Cl. 45—64)

1

This invention relates to piano benches of the type providing for storage of sheet music therein beneath the bench top.

The primary object of the present invention is to provide a bench of the above kind in which the sheet music may be filed away in an orderly manner and so that the performer may have ready access to the sheet music while remaining seated on the bench.

A further object of the invention is to provide a bench of the above character in which the sheet music is so filed as to facilitate ready access to and selection of the desired piece of music.

Still another object is to provide a bench of the above kind which is comparatively simple in construction, economical to manufacture, and extremely convenient and easy to use.

The invention consists in a novel form, combination and arrangement of parts hereinafter more fully described, shown in the accompanying drawings and claimed.

In the drawings:

Figure 1 is a rear elevational view of a piano bench constructed in accordance with the present invention.

Figure 2 is an end elevational view thereof.

Figure 3 is a top plan view of the same.

Figure 4 is an enlarged transverse section taken on line 4—4 of Figure 1.

Figure 5 is a fragmentary view, greatly enlarged, and more clearly illustrating a detail of the construction as shown in Figure 4.

Figure 6 is an enlarged longitudinal section taken on line 6—6 of Figure 2.

Figure 7 is a fragmentary section of the construction as shown in Figure 6, with the lid section of the bench opened.

Figure 8 is a view similar to Figure 6, showing a modification.

Referring in detail to the drawings, the present piano bench embodies a frame which includes four corner supporting legs 5 and relatively long similar front and rear rails 6 and similar shorter end rails 7 which rigidly connect the upper ends of the legs 5. The rails 6 and 7 are of flat form and vertically disposed edgewise so that their upper edges are flush with the upper ends of the legs 5. Also, the ends of the rails 6 and 7 are preferably joined to the legs by mortise and tenon joints as generally indicated by dotted lines at 8. The legs 5 at each end of the bench are rigidly connected near their lower ends by transverse brace bars 9, and these

2

brace bars 9 are rigidly connected intermediate their ends by a longitudinal brace bar 10.

A horizontal sheet music rack is mounted within the frame and comprises a casing 11 which is open at one end, and horizontal partitions 12 dividing the casing into superposed compartments 13 for reception of the sheet music. The partitions 12 gradually recede relative to each other at the open end of the rack in an upward direction, so that when the sheets of music are placed in the rack, an end of each sheet of music will project beyond the adjacent end of the sheet of music in the next higher compartment for revealing the title thereon and thereby facilitating ready access to and selection of any desired sheet of music. This relative disposition of the sheets of music in the rack is insured by providing the compartments of similar depth through the use of an inclined wall 14 at the closed end of the rack.

A flat bench top is provided on the frame including a fixed section 15 at one of the frame forming a seat section, and a vertically swinging section 16 at the other end of the frame forming a lid section adapted to be opened to permit access to the sheet music filed in the rack. The lid section 16 is preferably hinged at its outer end to the adjacent end rail 7 as at 17, suitable means being provided at the inner ends of the top sections 15 and 16 to latch the latter section in closed position, as at 18.

In the embodiment of Figures 1 to 7 inclusive, the front and rear rails 6 have longitudinal grooves in the inner faces thereof as at 19, said grooves extending from a point beyond the inner end of the seat section 15 through the ends of the rails 6 remote to the lid section 16. These grooves 19 are horizontal and horizontally aligned and form runways for ball bearing rollers 20 mounted on opposite sides of the rack casing 13 adjacent the front and rear ends of the rack. As shown more clearly in Figure 5, a bar 21 may be secured to each side of the rack casing 11 and provided with openings to receive headed pins 22 on which the rollers 20 are journaled. The rack is preferably assembled to the rails 6 prior to assembly of the frame by connection of the rails 6 and 7 to the legs 5. It will thus be seen that the rack is mounted for horizontal movement longitudinally of the bench from a position completely beneath the fixed top section 15 as shown in Figure 6 to a position partially projecting beyond the inner end of said section 15 as shown in Figure 7, or vice versa. When the rack is in the position of Figure 7, it is located so

that its open end is revealed beyond the inner end of the seat section 15 when the lid section 16 is opened. The lid section 16, in this embodiment, is operatively connected to the rack for shifting it in such a manner that said rack is moved to the position of Figure 6 when the lid section 16 is closed and to the position of Figure 7 when the lid section is opened. For this purpose, toggle links 23 connect the rack at its open end with the end of the frame to which the lid section 16 is hinged, and a further link 24 connects one of the toggle links 23 intermediate its ends with the lid section 16 adjacent its hinged end. Thus, when the lid section 16 is open, the toggle links are folded upwardly so that the rack is drawn past the inner end of the fixed lid section 15 where the open end of the rack is revealed and so that selection and removal of the sheet music in the rack is facilitated. The performer can remain seated on the lid section 15 when opening and closing the lid section 16, a desirable advantage over prior benches in which the entire lid opened and compelled the performer to rise to secure the music and then sit down on the bench again before being ready to play the piano.

If desired, the music sheet holding capacity of the bench may be increased by providing a further smaller sheet music rack 25 on the underside of the lid section 16 so that its open end is disposed uppermost when said lid section 16 is open. The shifting of the main rack permits the use of this second or supplemental music sheet rack 25 because the main rack shifts out of the way of the supplemental rack when the lid section 16 is closed.

The modification of Figure 8 is similar to the form of Figures 1 to 7 inclusive, except that the rack 11, 13, 14 is rigidly mounted in a fixed position within the frame of the bench and no connection is provided between it and the hinged lid section 16 because the rack is not moved or shifted. Under these circumstances, the rack is permanently located directly beneath the bench top so that its open end projects beyond the inner end of the fixed section 15 and is revealed beyond the inner end of said section 15 when the lid section 16 is opened. Obviously, the size and capacity of the main rack may be varied according to the needs and the size of the bench. In the embodiment of Figures 1 to 7 inclusive, engagement of the front rollers 20 with the inner ends of the grooves 19 properly limits the opening movement of lid section 16. When the lid section 16 is fully open, it is preferably in a substantially vertical position, and where the rack is stationary as in Figure 8, a suitable slotted link 26 may be hinged to the lid section 16 and arranged to coat with a pin 27 carried by the adjacent rail 6 to limit the opening of the lid section. Otherwise, the construction of both forms is similar, and like parts are indicated by similar reference characters.

From the foregoing description, it is believed that the construction, operation and advantages of the present invention will be readily understood and appreciated by those skilled in the art. Minor changes in details of construction are contemplated, such as fairly fall within the spirit and scope of the invention as claimed.

What we claim is:

1. A piano bench comprising a frame including corner supporting legs, and front, rear and end rails rigidly connecting the upper ends of the legs, a horizontal sheet music rack mounted within

the frame and comprising a casing open at one end and closed at the other end, and fixed horizontal partitions dividing the casing into similar superposed compartments, said partitions and compartments gradually receding relative to each other at said one end in an upward direction, and a flat bench top on the frame including a fixed section secured on one end of the frame and forming a fixed seat section, and a vertically swinging section hinged on the other end of the frame and forming a lid section adapted to be opened to permit access to sheet music filed in the rack, said rack being located and always remaining in a horizontal position directly beneath the bench top and being positioned so that its open end is revealed adjacent but just beyond the inner end of the seat section when the lid section is opened.

2. A piano bench comprising a frame including corner supporting legs, and front, rear and end rails rigidly connecting the upper ends of the legs, a horizontal sheet music rack mounted within the frame for horizontal movement longitudinally thereof and comprising a casing open at one end, and fixed horizontal partitions dividing the casing into superposed compartments, said partitions gradually receding relative to each other at said end in an upward direction, a flat bench top on the frame including a fixed section secured on one end of the frame and forming a seat section, and a vertically swinging section hinged on the other end of the frame and forming a lid section adapted to be opened to permit access to sheet music filed in the rack, and means operatively connecting the rack to the lid section for automatically shifting the rack entirely beneath the seat section when said lid section is closed and shifting it so that its open end is revealed adjacent but just beyond the inner end of said seat section when the lid section is opened.

3. A piano bench comprising a frame including corner supporting legs, and front, rear and end rails rigidly connecting the upper ends of the legs, a horizontal sheet music rack mounted within the frame for horizontal movement longitudinally thereof and comprising a casing open at one end, and fixed horizontal partitions dividing the casing into superposed compartments, said partitions gradually receding relative to each other at said end in an upward direction, a flat bench top on the frame including a fixed section secured on one end of the frame and forming a seat section, and a vertically swinging section hinged on the other end of the frame and forming a lid section adapted to be opened to permit access to sheet music filed in the rack, and means operatively connecting the rack to the lid section for automatically shifting the rack entirely beneath the seat section when said lid section is closed and shifting it so that its open end is revealed adjacent but just beyond the inner end of said seat section when the lid section is opened, and a supplemental music sheet rack fixed on the underside of said lid section, the first named rack being shiftable out of the way of the second named rack when the lid section is closed.

4. A piano bench comprising a frame including corner supporting legs, and front, rear and end rails rigidly connecting the upper ends of the legs, a horizontal sheet music rack mounted in a fixed position within the frame and comprising a casing open at one end, and fixed horizontal partitions dividing the casing into superposed compartments, said partitions gradually receding relative to each other at said end in an upward direction,

and a flat bench top on the frame including a fixed section secured on one end of the frame and forming a seat section, and a vertically swinging section at the other end of the frame forming a lid section adapted to be opened to permit access to sheet music filed in the rack, the rack being permanently located directly beneath the bench top so that its open end projects adjacent but just beyond the inner end of the seat section and is revealed when the lid section is opened.
